UNITED STATES PATENT OFFICE.

WILLIAM FORBES MILLER, OF TORONTO, ONTARIO, CANADA.

GLOBE-MANIPULATOR.

1,092,940.

Specification of Letters Patent. Patented Apr. 14, 1914.

Application filed April 23, 1913. Serial No. 764,254.

To all whom it may concern:

Be it known that I, WILLIAM FORBES MILLER, a subject of the King of Great Britain, of the city of Toronto, in the county of 5 York, in the Province of Ontario, Canada, have invented certain new and useful Improvements in Globe-Manipulators, of which the following is the specification.

My invention relates to improvements in 10 electric light bulb inserters and extractors, and the object of the invention is to provide means whereby bulbs of this class may be easily inserted or extracted, by a person standing on the ground, from sockets located 15 in high positions, and therefore not easily accessible, and it consists essentially of an elevating pole, a tubular socket carried by the upper end of the pole, gripping jaws carried by the socket and co-acting therewith to grip 20 the bulb, and means for rotating the socket and opening and closing the jaws, operated from the lower end of the pole, as hereinafter more particularly explained by the following specification.

25 Figure 1, is a perspective view of my device. Fig. 2, is a perspective view on a smaller scale, showing a bulb and my apparatus in position ready for extracting the same. Fig. 3 is a perspective view of my 30 apparatus and bulb, showing the bulb gripped by the apparatus. Fig. 4 is a similar view showing the bulb extracted. Fig. 5, is a vertical section through my device. Fig. 6, is a modified form showing my device 35 adapted for extracting upwardly extending bulbs.

In the drawings like letters of reference indicate corresponding parts in each figure.

40 A is a pole preferably tubular and of any suitable length, the upper end being formed into standards A'.

A² is a slot extending through the pole for a purpose which will hereinafter appear.

45 B is a tubular member formed at its lower end into lugs B' extending into the standards A' and through which from the standards A' extends a pivoted pin B².

B³ is a vertical slot formed in the tubular portion B at one side of its lower end. The 50 upper end of the tubular portion is provided with an annular flange B⁴.

B⁵ is an annular, horizontal flange secured to the portion B intermediately of its height.

55 C is a sleeve loosely mounted on the member B between the flanges B⁴ and B⁵.

C' is a socket tube secured by screws C² to the rotatable portion C. The upper end of the socket tube C' is flared at C³ the flared portion being provided with a thin rubber covering C⁴ for a purpose which will 60 hereinafter appear. The tubular socket C' is also provided with vertical slots C⁵.

C⁶ are arms extending radially outwardly from the tubular socket C', preferably three in number.

C⁷ are jaws pivotally connected intermediately of their length to each of the arms C⁶.

C⁸ are extension pieces extending from the jaws C⁷ through the slot C⁵ into the interior of the tubular socket C' free of the interior 70 periphery thereof. The jaws C⁷ are preferably tipped with rubber as shown at C⁹.

E is a stem held vertically within the tubular portion B.

E' is a cap portion secured to the stem and 75 fitting within the tubular socket sleeve C'.

F are diametrically opposite set bearing arms extending from and secured to the tubular portion B.

F' is a supplemental bearing bracket secured to the arms F and provided with a depending U-shaped portion F² between which is pivoted a lever F³ on a pin F⁴ extending through the lever and the bracket. The inner end of the lever F³ extends as clearly 85 shown in Fig. 5 beneath the lower end of the stem E.

G is an arc-shaped bar forming part of the tubular portion B and concentric with the center of the pin B². The lower end of 90 the arc-shaped bar G extends through the slots A².

G' is a set screw extending through the tubular rod A against the bar G.

I are spring fingers secured to the tubular 95 socket C' at their lower end and bearing at their upper end against the laterally extending pins I' extending from the extension pieces of the jaws C⁷.

J and J' are cords secured to the tubular socket C' so as to wrap around the same in opposite directions. The cords J and J' extend through eyes F⁶ and F⁷ formed in the ends of the arms F and from these to the bottom of the pole A.

J² is an operating cord secured to the end of the lever F³.

Having described the principal parts involved in my invention I will briefly describe the operation of the same. When it 110

is necessary to extract the bulb from its socket, my apparatus is elevated by the pole A in proximity thereto as shown in Fig. 2 in the drawing, the cord J² having been pulled 5 so as to open the jaws C'. The jaws C' are opened by the inner end of the lever F³ bearing against the lower end of the stem E. When the outer end of the lever is pulled downwardly the stem E is raised vertically 10 carrying the cap portions E' into contact with the inner end of the extension pieces C⁸, drawing such ends inwardly toward the center of the tubular socket C' against the tension of the springs I. The pole A is then elevated so that the bulb passes between 15 the jaws C' into the flared end C⁹ of the tubular socket C'. The lever F³ is then released, the gripping jaws C' being carried against the bulb by the springs I so as to grip the same in the position shown in Fig. 3 of the drawing. The cord J' is then pulled rotating the tubular socket in the direction of arrow shown in Fig. 1. This rotary movement of course will be readily understood unthreads the bulb from the socket 20 freeing the same. The apparatus may then be lowered and the bulb removed. Another bulb may then be placed in position within the jaws of the apparatus and elevated to 25 the socket. The cord J is then pulled rotating the tubular socket C' in the opposite direction to that indicated by arrow thereby threading the new bulb into the socket. The cord J² is then pulled so as to open the jaws 30 C' releasing them from the bulb.

In cases where incandescent bulbs are fitted into brackets so as to project upwardly I provide a U-shaped section K in the pole A so that my apparatus will depend over the 40 bulb as shown in Fig. 6 when in position for gripping the same.

In cases where the electric light bulb extends from the bracket at an angle, my apparatus may be adjusted to a similar angle 45 by loosening the set screw G and swinging the tubular socket around on its pivoted form by the pin B² and thereby carrying the member G in its circumferential direction through the slot A² until the tubular socket 50 is adjusted to its required angular position. The set screw G may then be again tightened.

From this description it will be seen that I have devised a very simple device whereby 55 incandescent bulbs may be easily and quickly removed from their sockets or placed in position within the sockets when such socket is in a very high and inaccessible position, such as in the roof of a church or other building 60 having a vaulted roof.

What I claim as my invention is—

1. An electric light bulb inserter or extractor, comprising a tubular socket having a flared upper end rotatably mounted upon 65 the upper end of the pole, gripping jaws

carried by the tubular socket and having extension pieces extending into the interior of the socket, a sleeve member movable longitudinally within the socket, and means for operating such sleeve member from the lower end of the pole, and means for rotating the tubular socket operated from the lower end of the pole, as and for the purpose specified. 70

2. An electric light bulb inserter or extractor, comprising a tubular socket having a flared upper end rotatably mounted on the upper end of the pole, gripping jaws carried by the tubular socket and having extension pieces extending into the interior of the 80 socket, a sleeve member movable longitudinally within the socket, a stem depending upon the sleeve portion, a lever pivoted intermediately of its length projecting at one end beneath the stem and provided at its 85 opposite end with an operating cord extending to the lower end of the pole, as and for the purpose specified.

3. An electric light bulb inserter or extractor, comprising an elevating pole having a slotted hole extending therethrough, a bulb gripping device pivotally connected to the upper end of the pole and an arc-shaped bar formed concentric to the center of the pivotal connection secured at one end to the bulb gripping device and extending at its opposite end through the slotted hole, and means for locking the arc-shaped bar in position, as and for the purpose specified. 90

4. In an electric bulb manipulator, means for gripping the bulb comprising a tubular socket, gripping jaws carried by said socket, said jaws having extension pieces extending within the socket, means slidably within said socket adapted to engage the extension pieces 100 and open said jaws, and spring means for closing the jaws in and for the purpose described. 105

5. In an electric bulb manipulator, means for gripping the bulb comprising a tubular socket, gripping jaws carried by said socket, said jaws having extension pieces extending within the socket, longitudinally movable means within said socket adapted to engage said extension pieces and open said jaws, and spring means for closing the jaws for the purpose described. 110 115

6. In an electric bulb manipulator, means for gripping the bulb, comprising a tubular socket, gripping jaws carried by said socket, said jaws having extension pieces extending within the socket, a sleeve within said socket adapted to engage said extension pieces and open said jaws, and spring means for closing the jaws for the purpose described. 120 125

7. In an electric bulb manipulator, means for gripping the bulb, comprising, a tubular socket, gripping jaws carried by said socket, said jaws having extension pieces extending within the socket, a longitudinally movable 130

sleeve within said socket for opening said jaws and spring means for closing the jaws for the purpose described.

8. In an electric bulb manipulator, means for gripping the bulb comprising, a tubular socket, a bracket carried by said socket, gripping jaws carried by said bracket, said jaws having extension pieces extending within the

socket, means within said socket for opening said jaws, and spring means for closing the jaws for the purpose described.
